UNITED STATES PATENT OFFICE

JESSE T. HENDERSON, OF LAWRENCE, KANSAS

BUILT-IN ARCH FOR FOOTWEAR

Application filed June 11, 1929. Serial No. 370,056.

This invention relates to improvements in built-in arches for footwear.

The primary object of the invention is to provide an arch for footwear which may be built into the sole structure so that the said footwear will have the outward appearance of an ordinary shoe, boot or the like.

A further object of the invention is to provide an arch which will be slightly flexible in the region of the ball of the foot and will be extremely rigid at the heel portion.

A still further object of the invention is to provide an arch which will extend from the ball of the foot to and over the heel so that the latter may be connected thereto, whereby the heel will be held from gapping at the back and from tipping under or forwardly.

Another object of the invention is to provide an arch which may be standardized as to all of its parts and yet may be adjusted to adapt it to fit any sized shoe, boot, or other footwear.

Still another object of the invention is to provide an arch of the type above referred to which may be manufactured at a very nominal cost; one that may be applied very easily and quickly to any style footwear without altering the latter, whereby it may be incorporated into the shoe, or the like, either during or after manufacture thereof; and one that will be very efficient in performing its intended work.

Other objects and advantages of the invention will be apparent during the course of the following description:

In the accompanying drawing forming a part of this specification and in which like numerals are employed to designate like parts throughout the same,

Figure 1 is a fragmentary longitudinal sectional view of a lady's shoe, or the like, embodying this invention,

Figure 2 is a bottom plan view of the shoe disclosed in Fig. 1 with the heel and the out-

sole removed to better illustrate the manner of associating the arch with the shoe,

Figure 3 is a plan view of one part of the sectional arch,

Figure 4 is a plan view of the other part of the sectional arch, and

Figure 5 is a detail transverse sectional view illustrating the groove and rib bracing formations embodied in the the arch sections.

In the drawing wherein for the purpose of illustration is shown a preferred embodiment of this invention, the letter (A) designates in its entirety the upper of a shoe which further includes the counter (B). The shoe has the usual form of insole (C) and outsole (D) while a heel (E) is secured to the rear portion of the shoe in a manner specifically to be described at a later point.

The arch consists of two pressed metal sections (F) and (R), the section (F) being termed the front section, while the section (R) will be termed the rear section. These two sections are adapted to be positioned between the insole (C) and the outsole (D), as best illustrated in Fig. 1 and they will be adjusted longitudinally of each other so that the entire arch will extend from the counter (B) lengthwise of the shank portion (S) of the shoe to terminate in the region (T) of the ball of the foot. The rear section (R) is bifurcated at 10 to form the fingers 11. Fig. 2 clearly discloses these fingers as extending between the counter (B) and the rear end of the insole (C). Apertures 12 are formed at the rear end portion of the section (R) and cooperate with the slot 13 of the bifurcated end 10 to receive screws, or the like, 14 by means of which the heel (E) may be secured to the shoe. These screws 14 extend through the insole (C) and outsole (D) from the inside of the shoe and enter the heel (E) a suitable distance. The rear section (R) of the arch is of elongated formation and gradually tapering off in width from the thickest portion 14 to the portion 15 which occurs in the

80

85

90

region of the shank (S) of the shoe. The remaining end portion 16 is slightly wider than the portion 15. A rib and groove formation 17 is formed longitudinally of the section (R) 5 and functions to brace the same against bending. A plurality of apertures 18 are formed in the rib and groove formation 17 adjacent the rear end thereof while a second series of apertures 19 are formed beyond the 10 opposite end of the rib and groove formation 17. Inwardly bent ears 20 are formed on the opposite edges of the inner end portion 16 of the rear section (R) and laterally of the series of apertures 19.

15 The front section (F) of the arch is flared at its front end portion 21 and is formed with apertures 22 to receive tacks or the like by means of which this end of the arch may be secured to the shoe (A). Formed in and projecting beyond the remaining end portion 23 20 of this section (F) is a rib and groove formation 24 which terminates in a tongue 25 bent into the shape of a hook. An aperture 26 is formed intermediate the ends of the section while opposed notches 27 are cut into the 25 opposite edges.

Fig. 2 discloses the sections (F) and (R) as being assembled with the rib and groove formation 17 of the rear section 30 (R) fitting within the similar formation 24 of the front section. The hook shaped tongue 25 is received in one of the apertures 18, depending upon the relative position of adjustment of the two sections 35 with respect to each other. After this adjustment has been determined, a rivet 28 is passed through the aperture 26 of the section (F) and through the proper aperture of the series 19 in the section (R). It will 40 be appreciated that during the sliding adjustment of the two sections, the ears 20 will prevent separation of the sections. The front section (F) may be positioned within these 45 inwardly turned ears 20 by registering the latter with the notches 27 in the section (F).

With the arch assembled as illustrated in Figs. 1 and 2, the heel (E) will be prevented from gapping at the back or from tipping under or forwardly. The rib and groove 50 formations 17 and 24 will brace this rear portion of the arch and will make the same very rigid. A slight degree of flexibility will be present in the outer end portion of the front section (F). Due to the adjustability of the 55 sections with respect to each other, the arch may be adapted to any size or style footwear.

It is to be understood that the form of this invention herewith shown and described is 60 to be taken as a preferred example of the same, and that various changes in the shape, size and arrangement of parts may be resorted to without departing from the spirit of the invention or the scope of the subjoined 65 claims.

Having thus described the invention, I claim:

1. In a device of the type described, the combination with a shoe, or the like, having an insole, an outsole and a heel, of a sectional 70 reinforcing member positioned between the said soles and extending from the ball portion of the shoe to the counter, the sections of said member overlapping each other for a portion of their lengths, means for connecting one end of each section to the intermediate 75 portion of the other section, and means passing through both of the soles, the reinforcing member and into the heel for causing the said member to prevent the heel from tipping with respect to the shoe.

2. In a device of the type described, the combination with a shoe, or the like, having an insole, an outsole and a heel, of a sectional 80 reinforcing member positioned between the said soles and extending from the ball portion of the shoe to the counter, the sections of said member overlapping each other for a portion of their lengths, means for connecting one end of each section to the intermediate 85 portion of the other section, means for bracing the sections of said member at the shank portion of the shoe, and means passing through both of the soles, the reinforcing member and into the heel for causing the 90 said member to prevent the heel from tipping with respect to the shoe.

3. An arch and heel reinforcing device, comprising a pair of pressed metal members, means for adjustably connecting said members in partial overlapping relation with respect to each other, and medially extending means for bracing said members at their overlapped portions.

4. An arch and heel reinforcing device, 100 comprising a pair of pressed metal members, and means for adjustably connecting said members in partial overlapping relation with respect to each other, the overlapped portions of said members having interfitting rib and 105 groove formations located between the longitudinal edges of the members for bracing the 110 same against bending.

5. An arch and heel reinforcing device, 115 comprising a pair of pressed metal members, longitudinal means for reinforcing each of said members, and means for adjustably connecting said members in partial overlapping relation with respect to each other, said adjustable connecting means including a series 120 of apertures formed in the reinforcing means of one of said members and a tongue formed on the other member and adapted to enter any one of said apertures.

6. An arch and heel reinforcing device, 125 comprising a pair of pressed metal members, means for slidably connecting said members in partially overlapping relation with respect to each other, means formed in the overlapping portions of the members for bracing 130

the same against bending, and means formed in the bracing means for holding the members in proper relative adjusted positions.

7. An arch and heel reinforcing device, comprising a pair of pressed metal members arranged in partial longitudinal overlapping relation with respect to each other, means for longitudinally reinforcing said members, and means for adjustably connecting the inner end of each of said members to the adjacent intermediate portion of the other member.

In testimony whereof, I affix my signature.
JESSE T. HENDERSON.
